US00D925848S

(12) **United States Design Patent** (10) **Patent No.:** **US D925,848 S**
Johnson (45) **Date of Patent:** **** Jul. 20, 2021**

(54) **SURFACE CLEANING HEAD**(71) Applicant: **SharkNinja Operating, LLC**,
Needham, MA (US)(72) Inventor: **Owen R. Johnson**, Needham, MA (US)(73) Assignee: **SharkNinja Operating LLC**,
Needham, MA (US)(***) Term: **15 Years**(21) Appl. No.: **29/658,928**(22) Filed: **Aug. 3, 2018****Related U.S. Application Data**

(63) Continuation of application No. 29/605,401, filed on May 25, 2017, now Pat. No. Des. 853,063.

(51) **LOC (13) Cl.** ..... **15-05**(52) **U.S. Cl.**USPC ..... **D32/32**(58) **Field of Classification Search**USPC D32/31-34, 15-25, 29; 15/415.1

Primary Examiner — Kimberly Barnes(74) *Attorney, Agent, or Firm* — Grossman Tucker Perreault & Pfleger, PLLC(57) **CLAIM**

The ornamental design for a surface cleaning head, as shown and described.

DESCRIPTION

FIG. 1 is a perspective view of a surface cleaning head showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The broken lines are included for the purpose of illustrating portions of the surface cleaning head that form no part of the claim.

1 Claim, 8 Drawing Sheets# US D925,848 S
